UNITED STATES PATENT OFFICE

ANGELINE P. GRABHAM, OF MINERAL POINT, WISCONSIN.

IMPROVEMENT IN QUILTING-FRAME CLAMPS.

Specification forming part of Letters Patent No. 159,690, dated January 26, 1875; application filed April 25, 1874.

To all whom it may concern:

Be it known that I, ANGELINE P. GRABHAM, of Mineral Point, in the county of Iowa and State of Wisconsin, have invented a new and Improved Frame-Holder; and I do hereby declare that the following is a full and exact description thereof, reference being had to the accompanying drawing and to the letters of reference marked thereon.

The nature of my invention consists in an adjustable clamp and standard-socket attached to the clamp, all for the purpose of securing and holding fast the bars of quilt-frames at their points of intersection when they are arranged around the margin of a bed-quilt, for the purpose of giving the quilt tension to facilitate its stitching by the manufacturer, and for supporting the frames and quilt at a convenient height from the floor.

The general form of the frame-holder resembles the letter **U**, Figure 1, made of cast or other iron or steel. At the point of one of the jaws of the frame-holder, marked **A**, is a matrix passing through the jaw, in which works a thumb-screw, **B**, against the spring **C**. On the convex side of the clamp, at the point **D**, is securely attached the standard-socket **E**, for the purpose of receiving a standard, by means of which the quilt bars or frames are to be supported above the floor after being made fast in the frame-holder by means of the adjustable thumb-screw **B**. At each intersection of the four frames, which surround the margin of the quilt, the frame-holder is to be applied, in a horizontal position, in either angle of the intersections of the bars or frames,

by passing the points of intersection within the cavity of the frame-holder to its concave surface; and, by means of the adjustable thumb-screw **B**, the bars or frames are securely fastened together at the points of intersection.

The frame-holder consists of a piece of cast or other iron, steel, or other metal, or wood, modeled in the shape of the letter **U**, in one of the points of which is inserted an adjusting thumb-screw, which screw points toward the opposite point of the frame-holder. Within the inner surface of the point in which the thumb-screw is inserted, and bearing against the inner point of the screw, is a spring, which is driven by the thumb-screw against the frame bar or fabric, and prevents damage by the thumb-screw. On the convex surface of the frame-holder, and farthest from the thumb-screw, is securely attached a standard-socket, set parallel with the convex surface, for the purpose of receiving a standard to support the bars or frames above the floor.

What I claim as my invention, and desire to secure by Letters Patent, is—

A clamp for quilting-frames, consisting of the **U**-shaped device, as shown in Fig. 1 of the accompanying drawing, provided with the thumb-screw **B**, guard-spring **C**, and the standard-socket attachment **E**, all combined to operate substantially as and for the purpose set forth.

ANGELINE P. GRABHAM.
